(57) **CLAIM**

The ornamental design for a hair straightener, as shown and described.

DESCRIPTION

FIG. 1 is a top, right side perspective view of a hair straightener showing our new design, the jaw of the hair straightener in a closed position;

FIG. 2 is a front elevation view of FIG. 1;

FIG. 3 is a rear elevation view of FIG. 1;

FIG. 4 is a left side elevation view of FIG. 1;

FIG. 5 is a right side elevation view of FIG. 1;

FIG. 6 is a top plan view of FIG. 1;

FIG. 7 is a bottom plan view of FIG. 1;

FIG. 8 is a top, left side perspective view of the hair straightener with the jaw in an open position; and,

FIG. 9 is a top, right side perspective view of FIG. 8.

The broken lines in the drawings depict portions of the hair straightener that form no part of the claimed design.
